BARREL STOP FOR BREAKDOWN FIREARMS

Filed Dec. 3, 1929

UNITED STATES PATENT OFFICE

FRANK F. BURTON, OF MOUNT CARMEL, CONNECTICUT, ASSIGNOR TO WINCHESTER REPEATING ARMS COMPANY, OF NEW HAVEN, CONNECTICUT, A CORPORATION OF DELAWARE

BARREL STOP FOR BREAKDOWN FIREARMS

Application filed December 3, 1929. Serial No. 411,237.

This invention relates to an improvement in barrel-stops for breakdown firearms and has for one of its objects the provision of a barrel-stop of the type referred to which will 55 minimize the need for excessively accurate fitting of the parts.

Another object of my invention is to provide a barrel-stop which will function continuously with the minimum of wear, so that 10 the angle which the barrel-unit will assume when "broken down" with respect to the frame and butt-stock unit will be substantially the same throughout a long period of service.

15 A further object of my invention is to provide a barrel-stop of a type which will require, for its accommodation, the minimum cutting away of the metal of the frame, whereby the said frame may be of such size 20 and form as to be both light and symmetrical and still possess an adequate margin of strength.

With the foregoing and other objects in view, my invention consists in a barrel-stop 25 for breakdown firearms having certain details of construction and combinations of parts as will be hereinafter described and particularly recited in the claims.

In the accompanying drawings:

30 Fig. 1 is a broken view, partly in side elevation and partly in central longitudinal section, of a double-barrel shotgun equipped with my improved barrel-stop;

Fig. 2 is a corresponding view with the 35 barrel-unit shown in its broken-down position;

Fig. 3 is a transverse sectional view taken on the line 3—3 of Fig. 1;

Fig. 4 is a broken top or plan view of the 40 frame; and

Fig. 5 is an enlarged-scale detached perspective view of the floating barrel-stop-bar.

The embodiment of my invention herein chosen for illustration is shown as installed 45 in a double-barreled breakdown shotgun, though it is obvious that the use of my invention is not so limited, since it may be employed in connection with other types of breakdown firearms.

50 The shotgun comprises the usual frame-

body 10 formed at its bottom-edge with a forward extension 11 which in turn is formed with a longitudinal vertically-arranged slot or passage 12 closed at its bottom-end by the forward end of a trigger-plate 13 having a 55 trigger-guard 14 within the looped form of which a pair of triggers 15 are located. The frame 10, as is usual in firearm construction, is secured to the forward end of a butt-stock 16 in any approved manner.

To provide for pivoting the barrel-unit, which comprises in the main a pair of barrels 17 and 18 and a fore end 19. I provide a transverse trunnion-pin 20 which extends 60 across the slot 12 in the extension 11 of the frame-body 10 and is supported in the opposite sidewalls thereof. This pin is partly embedded, so to speak, in the forward wall of the slot 12 but has the major portion of its circumference rearwardly exposed within the 65 forward end of the said slot, as clearly shown in Figs. 1 and 2 of the drawings.

The barrel-unit, comprising the barrels 17 and 18 and the fore end 19, as well as other incidental features not shown, is formed centrally in its underside with a longitudinally-arranged depending lug 21 adapted to fit 70 within the slot 12 of the frame-body 10, as clearly shown in Figs. 1 and 3 of the drawings. The forward end of the lug 21 is 75 formed with a forwardly-facing substantially-semicircular notch 22 adapted to rock upon the trunnion-pin 20 before referred to.

The lower forward corner of the extension 11 of the frame-body 10 is rounded off, as 80 at 23, concentrically with the trunnion-pin 20, so that the fore end-shoe 24 of the fore end 19 will snugly fit against the frame-body 10 in all positions of the barrel-unit in its swinging movement with respect to the said frame-body; the rear face of the said shoe being 85 formed, as shown, with a cylindrically-contoured concave surface 25 conforming to the curvature of the surface 23 of the extension 11 and resulting in the formation of a relatively-90 sharp terminal 26.

For the purpose of limiting the breakdown movement of the barrel-unit with respect to the frame-body 10, I employ a floating barrel-stop-bar 27 which is cylindrical in cross-sec- 95 100

tion and is formed at its respective opposite ends with notches 28 and 29 respectively resulting in the formation of upwardly-facing stop-shoulders 30 and 31.

5 The barrel-stop-bar 27 above referred to is mounted with freedom for limited transverse bodily movement and axial and endwise rocking movement in a vertically-extending transverse slot 32 formed in the depending-lug 21 of the barrel-unit intermediate the ends thereof.

10 For the purpose of preventing the endwise displacement of the bar 27 I form the same with a diametrical passage 33 for the reception of a guide-pin 34 which it freely fits. The said guide-pin extends vertically through the slot 32 and is formed at its lower end with an enlarged threaded head 35 which is screwed into an internally-threaded vertical 15 bore 36 opening through the under-face of the said lug 21.

15 The upper and major portion of the passage 33 aforesaid is enlarged to form a pocket 37 for the reception of a helical spring 38 encircling the guide-pin 34 and seating at 20 its upper end against the top wall of the slot 32 and at its opposite end against the bottom wall of the pocket 37, as clearly shown in Fig. 3 of the drawings. The upper end 25 of the pin 34 is seated in a bore 39 arranged axially in line with the threaded bore 36 and extending upward from the upper wall of the slot 32, which it intersects.

30 The over-all length of the floating barrel-stop-bar 27 above described is greater than the width of the lug 21, so that its opposite ends project beyond the opposite faces of the latter and are entered into inclined clearance-grooves 40 and 41 formed in the side-walls of 35 the slot 12 in the extension 11 of the frame-body 10.

35 The clearance-grooves 40 and 41 intersect the upper surface of the body-extension 11 and slope forwardly and downwardly therefrom, as clearly shown in Fig. 2 of the drawings, so that their respective upper walls constitute abutment-shoulders 42 and 43 for engagement by the stop-shoulders 30 and 31 respectively of the floating barrel-stop-bar 27 40 to limit the breakdown movement of the barrel-unit with respect to the frame-body 10.

45 Normally and as shown in Fig. 1 of the drawings, the lug 21 of the barrel-unit is housed within the vertical slot 12 in the body-extension 11 and the respective opposite ends of the bar 27 positioned in the inclined clearance-grooves 40 and 41.

50 Now when the barrel-unit is unlocked in any approved manner and swung downward into the position shown in Fig. 2 of the drawings, the stop-shoulders 30 and 31 of the bar 27 will be brought into engagement with the abutment-shoulders 42 and 43 in the side-walls of the slot 12 and owing to the fact 55 that the bar 27 is mounted with capacity

for both axial and endwise rocking movement, any irregularities of the positioning or formation of the abutment-shoulders 42 and 43 or the stop-shoulders 30 and 31 will be automatically compensated for, so that 60 wear will be minimized and the barrel-unit checked in its breakdown movement at the same angle throughout a long period of use.

65 By providing for the compensatory action of the floating barrel-stop-bar 27 as above described, the effect of the battering action incident to the repeated engagement of the stop-shoulders 30 and 31 with the abutment-shoulders 42 and 43 is so minimized that 70 no burring or other distortion takes place in the engaging parts, with the result that the breakdown action of the gun is uniformly smooth throughout a long period of use.

75 Furthermore by mounting the barrel-stop-bar 27 so that it has capacity for bodily lateral movement or, more specifically as shown, vertical bodily movement in the lug 21, the width of the inclined grooves 40 and 41 may be kept at a minimum, inasmuch 80 as the said bar need not partake of the full movement of the lug 21 from the normal position of the same (Fig. 1) to its broken-down position (Fig. 2).

85 The spring 39, by tending to maintain the bar 27 in the bottom of the slot 32, serves to facilitate the reentry of the ends of the said bar into the grooves 40 and 41 when the frame- and barrel-units are being reassembled after being "taken down."

90 I claim:

95 1. In a breakdown firearm, the combination with the relatively-pivoted frame-unit and the barrel-unit thereof; of a barrel-stop-member carried by the said barrel-unit with capacity for endwise rocking movement with respect thereto; and a pair of complementary abutments carried by the said frame-unit in position to be engaged by the opposite ends of the said stop-member; whereby the engagement of the opposite ends of the said stop-member with both of the said abutments in the frame-unit is insured.

100 2. In a breakdown firearm, the combination with the relatively-pivoted frame-unit and the barrel-unit thereof; of a barrel-stop-member carried by the said barrel-unit with capacity for both axial and endwise rocking movement with respect thereto; and a pair of complementary abutments carried by the said frame-unit in position to be engaged by the opposite ends of the said stop-member; whereby the engagement of the opposite ends of the said stop-member with both of the said abutments in the frame-unit is insured.

105 3. In a breakdown firearm, the combination with the relatively-pivoted frame-unit and the barrel-unit thereof; of a barrel-stop-member carried by the said barrel-unit with

capacity for lateral bodily movement and both endwise and axial rocking movement with respect thereto; and a pair of complementary abutments carried by the said frame-unit in position to be engaged by the opposite ends of the said stop-member; whereby the engagement of the opposite ends of the said stop-member with both of the said abutments in the frame-unit is insured.

4. In a breakdown and takedown firearm, the combination with the relatively-pivoted frame-unit and the barrel-unit thereof; of a barrel-stop-member carried by the said barrel-unit with capacity for substantially vertical bodily movement with respect thereto; and a pair of complementary abutments carried by the said frame-unit in position to be engaged by the opposite ends of the said stop-member; whereby the take down and assembly of the frame-unit and barrel-unit is facilitated.

5. In a breakdown firearm, the combination with the frame-body and the barrel-lug thereof; of a floating barrel-stop carried by the said lug and coacting with the said frame-body to limit the breakdown movement.

6. In a breakdown firearm, the combination with the relatively-pivoted frame-unit and barrel-unit thereof; of a lug offsetting from the said barrel-unit near the rear end thereof; a barrel-stop-bar carried by the said lug with capacity for endwise rocking movement with respect thereto; and a pair of complementary abutments carried by the frame-unit in position to be engaged by the opposite ends of the said rocking stop-bar; whereby the engagement of the opposite ends of the said stop-bar with both the two said abutments in the frame is insured.

7. In a breakdown firearm, the combination with the relatively-pivoted frame-unit and barrel-unit thereof; of a lug offsetting from the said barrel-unit near the rear end thereof and formed with a transverse passage; a barrel-stop-bar extending transversely through the passage in the said lug with capacity for endwise compensatory rocking movement therein; and a pair of complementary abutments carried by the frame-unit in position to be engaged by the opposite ends of the said rocking stop-bar; whereby the engagement of the opposite ends of the said stop-bar with both the two said abutments in the body-unit is insured.

8. In a breakdown firearm, the combination with the relatively-pivoted frame-unit and barrel-unit thereof; of a lug offsetting from the said barrel-unit near the rear end thereof; a barrel-stop-bar carried by the said lug with capacity for both axial and endwise rocking movement with respect thereto and provided at its opposite ends respectively with a flat upwardly-facing stop-surface;

and a pair of complementary abutment-shoulders carried by the frame-unit and positioned to be engaged by the stop-surfaces of the said stop-bar.

9. In a breakdown firearm, the combination with the relatively-pivoted frame-unit and barrel-unit thereof; of a lug offsetting from the said barrel-unit near the rear end thereof; a barrel-stop-bar carried by the said lug with capacity for lateral bodily movement and endwise and axial rocking movement with respect thereto and provided at its opposite ends respectively with a flat upwardly-facing stop-surface; and a pair of complementary abutments carried by the frame-unit and positioned to be engaged by the stop-surfaces of the said stop-bar.

10. In a breakdown firearm, the combination with the relatively-pivoted frame-unit and barrel-unit thereof; of a lug offsetting from the said barrel-unit near the rear end thereof and formed with a vertically-extending transverse slot; a barrel-stop-bar extending transversely through the slot in the said lug with capacity for lateral bodily movement therein; a spring arranged to normally hold the said bar in the bottom-portion of the slot in the said lug; and a pair of complementary abutments carried by the said frame-unit in position to be engaged by the opposite ends of the said rocking stop-bar.

11. In a breakdown firearm, the combination with the relatively-pivoted frame-unit and barrel-unit thereof; of a lug offsetting from the said barrel-unit near the rear end thereof and formed with a vertically-extending transverse slot; a barrel-stop-bar extending transversely through the passage in the said lug with capacity for lateral bodily movement therein; a vertically-arranged pin engaging the said bar to prevent its endwise displacement; a spring encircling the said pin and arranged to normally hold the said bar in the bottom-portion of the slot in the said lug; and a pair of complementary abutments carried by the said frame-unit in position to be engaged by the opposite ends of the said rocking stop-bar.

In testimony whereof, I have signed this specification.

FRANK F. BURTON.
